UNITED STATES PATENT OFFICE.

HERMAN ROTHKIRCH, OF NEW YORK, N. Y.

PHONOGRAPH.

Application filed November 8, 1921. Serial No. 513,747.

To all whom it may concern:

Be it known that I, HERMAN ROTHKIRCH, a citizen of the United States, and resident of the borough and county of Queens, city 5 and State of New York, have invented certain new and useful Improvements in Phonographs, of which the following is a specification.

My invention relates to phonographs and 10 has for its object to provide such instruments with a tone arm constructed entirely of wood in a novel manner and whereby all objectionable and foreign noises are eliminated from the reproduction of the record. 15 A further object of the invention is to provide such a tone arm with a reproducer constructed as an integral part thereof and consisting, excepting as to the diaphragm and needle arm, also entirely of wood. Other 20 more specific objects of my invention will appear from the description hereinafter and the features of novelty will be pointed out in the appended claim.

The present application is, in part, a continuation of another application filed by me in the United States Patent Office on or about April 7, 1921, Serial No. 459,300.

In the accompanying drawings, which 30 illustrate examples of my invention without defining its limits, Figure 1 is a perspective view of my improved tone arm and so much of a phonograph as is necessary to illustrate the invention; Fig. 2 is an end elevation of the tone arm; Fig. 3 is a fragmentary, inverted plan view thereof; Fig. 4 is an elevation of the combined tone arm and reproducer, with parts in section; Fig. 5 is a longitudinal section thereof; Fig. 6 is a section on the line 6—6 of Fig. 4; Fig. 7 is a section on the line 7—7 of Fig. 4; Fig. 8 is a similar view on the line 8—8 of Fig. 4; Fig. 9 is a detail section on the line 9—9 of Fig. 8, and Fig. 10 is a detail section illustrating a sound controlling device which 45 may form a part of the construction.

In the drawings, 10 indicates the rotating table of a phonograph mounted in the customary manner upon an arbor 11 which, as usual, comprises a part of and is operated by a spring motor in the well known way. 50 12 represents the casing of a phonograph which may be constructed in any conventional manner to include a sound conduit 13 and such other features as usually are found

in instruments of the character referred to. 55 In the form shown in Figs. 1, 2 and 3 the tone arm 14 is of rectangular cross-section and is constructed entirely of wood in a curved form, as shown in Fig. 1, and at its forward end communicates with and carries 60 the reproducer 15 which, in this form, may be of any existing type or constructed in any special manner for special co-operation with the tone arm in question. When constructed as a separate unit in the customary way, the reproducer 15 may be detachably secured to the tone arm in any conventional manner. The upper and lower walls *a* and *b*, respectively, of the tone arm 14 are bent 65 into curved form in the direction of their length whereby at least some of the fibres of the wood are placed under tension and the frequency of vibration of the tone arm is altered to improve its qualities as a sound conduit. The side walls *c* of the tone arm 70 are curved to properly fit the upper and lower walls *a* and *b* thereof, as shown in Fig. 1, and may be connected therewith by gluing or in any other suitable manner. 75 The tone arm 14, in the illustrated example shown in Figs. 1, 2 and 3, extends through a suitable opening 16 in the top of the casing 12, so that its inner end communicates 80 with the sound conduit 13. The tone arm may be mounted for support in a horizontal 85 plane in any convenient way and may, for instance, be provided with a pivot member 17 of wood which is seated in a socket 18 formed in a coupling head 19 suitably mounted within the casing 12. In order to 90 secure the tone arm 14 against unintentional removal without interfering with its pivotal movements, the pivot 17 may be provided with a lug 20 adapted to project beneath a flange 21 of the coupling head 19. 95 The flange 21 extends only partly about the coupling head 19 and forms an opening 22 through which the lug 20 may be passed in one position to disconnect the tone arm 14 from the coupling head. The opening 22 is 100 so located that it is necessary, in order to permit disconnection of said tone arm from the coupling head, to bring the tone arm to a position other than the position assumed by it in the operation of the instrument. While it is thus possible, with this arrangement, to readily disconnect the tone arm when this is desired for any reason, said 105

tone arm is efficiently protected against unintentional or accidental disengagement from the coupling head 19.

In the form shown in Figs. 4 to 8 inclusive, the tone arm includes, as an integral part, the reproducer 15^a, which is constructed of wood and consists of a casing 23 formed with an interior spiral passage 24 constituting a continuation of the tone arm passage and terminating in an opening 25 in the front face of the casing 23. The passage tapers gradually in a direction toward the opening 25, as shown in Fig. 5, and also becomes gradually smaller in a transverse direction as it approaches said opening, as illustrated in Fig. 6. The combined reproducer and tone arm may be said to comprise a sound conduit of which the casing 23 is the head and the tone arm 14 the body. An annular flange 26 is located upon the front face of the casing 23 in concentric relation to the opening 25, which it encircles, and forms a support for the customary diaphragm 27 which is fastened in place by means of a ring 28 of wood and screws 29, as shown in Fig. 4. The ring 28 serves as a support for bearing members 30, which are also of wood, and between which the stylus arm 31 is pivotally mounted by means of pivot screws 32 in the well known manner; at one end, said arm 31 is connected with the diaphragm 27, as usual, while at its free end said arm is provided with the customary socket 33 in which the needle is removably secured by means of the conventional set screw 34.

In the form of tone arm being described the walls *a*, *b* and *c* are preferably bowed to a slight extent, as shown in Fig. 7, whereby the fibres of the wood at the indicated points of these walls are placed under tension to still further increase the resonance of the tone arm; in the preferred form, the outward bowing of said walls is confined to the vicinity of the exit end of the tone arm, said walls being gradually flattened out as the free end of the tone arm is approached.

The tone arm under discussion may, as shown, also be provided with members 35 which project outwardly from the walls *a*, *b* and *c* and together constitute a circular flange or disk whereby the opening 16 of the casing 12 is covered, as indicated in Fig. 5; the members 35 are shaped so as not to interfere with the rocking movements of the tone arm. In the preferred form the members 35 engage the walls *a*, *b* and *c* only at spaced points and are free therefrom between such points, as shown in Fig. 7; with this arrangement opposition to the vibration of said walls by the action of the sound waves is reduced to a minimum and the resonance of the tone arm is not interfered with to any appreciable extent.

In the form of construction illustrated in Figs. 4 to 8 inclusive, the coupling head 19^a is pivotally mounted at 19^b to swing about a horizontal axis instead of being fixed as in Fig. 1. Similarly the pivot 17 is provided with a pin 20^a which corresponds to the lug 20 and which is arranged to extend and move beneath a flange 21^a corresponding to the flange 21 of Fig. 1. By bringing the tone arm to a position other than any position assumed by it in the operation of the instrument, said pin 20^a is moved from beneath the flange 21^a and thus permits the tone arm to be disconnected from the coupling head 19^a. By pivotally mounting the latter, as illustrated, the automatic adjustability of the tone arm to any vibrating or undulating movements of the record or table 10 is facilitated.

It will be understood that any of the features specifically set forth with respect to the form shown in Figs. 4 to 8 inclusive may be included in the form shown in Figs. 1 to 3 inclusive and vice versa.

By constructing the tone arm, in the manner described, entirely of wood in which at least some of the fibres are placed under tension the resonance of said tone arm is materially increased and the reproductive or tonal quality of the instrument is greatly improved. The absence of any metal in said tone arm also avoids the production of any metallic sounds when the record is being reproduced. The quality of the tone arm in particular and the instrument in general, from the standpoint of reproduction or tone, is still further increased by constructing the tone arm and reproducer as a unit, as shown in Figs. 4 to 8 inclusive. With this arrangement all metallic sounds are eliminated and the sound waves, free from any objectionable and disturbing sounds, are conducted by the passage 24 to the interior of the tone arm and permitted to gradually expand without losing any of their original qualities and to finally issue forth from the exit end of the sound conduit 13 in a maximum of volume and tonal purity. The tone arm, in all of its forms, is simple in construction and may be produced in a manner adapting it for co-operation with existing types of phonographs.

As shown in Fig. 10, a member 36 may be pivotally mounted upon the reproducer in such a manner that its one end is movable across the passage 24, preferably near its inlet end whereby the open area of said passage may be adjusted at this point to regulate the volume of sound escaping from the instrument. The member 36 extends beyond the casing 23 in the form of a readily accessible handle 37 whereby said member may be manipulated without effort to provide the desired regulation and also to pro-

duce predetermined effects, such as a gradual increase or decrease or both in the volume of sound.

Various modifications in the specific form shown and described may be made within the scope of the claim without departing from the spirit of my invention.

I claim:

In a phonograph, a tone arm of unbroken curved continuity constructed of wood,

said tone arm being of polygonal cross-section and having its walls curved in lengthwise directions and also bowed outwardly at predetermined points in transverse directions to place the wood fibres 15 under tension.

In testimony whereof I have hereunto set my hand.

HERMAN ROTHKIRCH.
